UNITED STATES PATENT OFFICE

YASUJIRO YOSHIDA, OF LOS ALTOS, CALIFORNIA

DESIGN FOR A LAMP

Application filed September 23, 1929. Serial No. 32,845. Term of patent 3½ years.

To all whom it may concern:

Be it known that I, YASUJIRO YOSHIDA, a citizen of Japan, residing at Los Altos, in the county of Santa Clara and State of California, have invented a new, original, and ornamental Design for Lamps, of which the following is a specification, reference being had to the accompanying drawings, forming a part thereof.

I claim:

The ornamental design for a lamp substantially as shown.

YASUJIRO YOSHIDA.
